CLAIM

The ornamental design for an air mattress for use in a casket, as shown and described.

DESCRIPTION

FIG. 1 is a perspective view of the air mattress for use in a casket embodying the design of the present invention;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof; and,

FIG. 6 is a bottom view thereof.

FIG. 1.

FIG. 6.

FIG. 3.

FIG. 2.

FIG. 5.

FIG. 4.
